(57) **CLAIM**

The ornamental design for a reed case, as shown and described.

DESCRIPTION

FIG. 1 is a perspective view of the reed case showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and

FIG. 8 is a perspective view thereof, showing the reed case in an alternate, opened position;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is an additional front elevation view thereof; and,

FIG. 16 is an additional perspective view thereof.

The broken lines in FIGS. 8, 9 and 15 illustrate either a reed or portions of the reed case, neither of which forms part of the claimed design.

1 Claim, 17 Drawing Sheets
